UNITED STATES PATENT OFFICE.

GUY C. ODOR, OF LIMA, OHIO.

TELEPHONE-DIRECTORY.

No. 857,662.

Specification of Letters Patent.

Patented June 25, 1907.

Application filed May 10, 1906. Serial No. 316,111.

To all whom it may concern:

Be it known that I, GUY C. ODOR, of Lima, in the county of Allen and State of Ohio, have invented certain new and useful Improvements in Telephone-Directories, of which the following is a specification.

This invention relates to improvements in that class of telephone directories which are used as an advertising novelty and which are designed to be applied to a telephone by removing the mouth piece of the transmitter, placing the directory in position, and then screwing back the mouth piece to hold the directory in proper position for use.

The object of my invention is to provide a directory of this class in which the entire amount of space on the directory proper may be used for directory purposes, while, at the same time, ample space is provided for advertising matter. I accomplish this, by the use of two disks, the under one of which is provided with names, while the upper one has an opening or gap through which the names may be exposed and on which upper disk similar advertising matter may be printed.

With this object in view, my invention consists in the telephone directory as will now be hereinafter more particularly described, illustrated in the accompanying drawings, and then definitely pointed out in the claim at the end hereof.

In the drawings accompanying and forming part of this application: Figure 1 is an elevation of my directory, and Fig. 2 is a section of the same.

Referring now to the details of the drawings by numerals: 1 and 2 represent two disks preferably formed of cardboard and which are, in use, arranged one over the other. The upper disk 1 is provided with a central aperture 3 and an enlarged sight opening 4 through which may be exposed any matter which may be on the under disk 2. Since this directory is principally to be used as an advertising novelty, this upper disk 2 may have any suitable advertising matter printed thereon, as illustrated in Fig. 1. The under disk 2 has an enlarged opening in the center and at its periphery is formed with a number of divisions on which may be printed the letters of the alphabet. Radiating from the central aperture to the periphery of the disk are a series of lines on which may be

written the various names and telephone numbers as is usual with this class of directory. Underneath this second disk 2 is a base 6 which may be of any desired shape and the under disk 2 is loosely placed between this base 6 and the upper disk 1. The disk 2 is designed to have a movement between the upper disk 1 and the base 6, and to permit this, a ring 8 is employed which fits within the enlarged opening in the under disk 2, and this ring 8 is securely glued, or otherwise fixed, both to the upper disk 1 and to the base 6. By this construction, the upper disk 1 and the base 6 are secured together and at the same time the under disk or directory 2 may be rotated between the upper disk 1 and the base 6 around the ring 8 as a center. Both the ring 8 and the base 6 have openings 9 and 10 in their centers which are of the same size as the opening 3 in the upper disk 1, and these openings are designed to permit the telephone directory as an entirety to be properly secured to the telephone in the usual manner. In other words, the directory may be applied by removing the mouthpiece of the transmitter, placing the directory in place, and then securing the mouthpiece down tight, which holds the directory in its proper position for use. Since the directory is held by the mouthpiece only immediately around the center openings 3, 9 and 10, it is easily to be seen that the mouthpiece does not bind the center disk 2 between the upper disk 1 and the base 6, but, on the contrary, the under disk or directory 2 may be freely rotated to bring any appropriate names underneath the opening 4 to expose those names to view.

My invention is so simple that no further description of its operation is necessary.

What I claim as new is:

In a directory of the character described the combination with an upper disk and a base, each centrally apertured, of a smaller disk formed separately from said upper disk and said base and located between them and also having a central aperture, a directory disk centrally apertured to inclose the smaller disk and adapted to be rotated around it, said directory disk being located between the upper disk and the base and the upper disk having a sight opening through which matter on the directory disk may be exposed, the said upper disk, the base and

the smaller disk being secured together and constructed and arranged to be clamped by the mouth piece of a telephone transmitter so that they are firmly held while the directory sheet may be rotated around the smaller disk and between the base and the upper disk, substantially as described.

Signed by me at Lima, Ohio, this 7th day of May 1906.

GUY C. ODOR.
